(57) **CLAIM**

I claim the ornamental design for a tote bag, as shown and described.

DESCRIPTION

FIG. 1 is a perspective view of a tote bag.

FIG. 2 is a perspective view of the tote bag with the straps in a second position.

FIG. 3 is a front elevation view of the tote bag.

FIG. 4 is a back elevation view of the tote bag.

FIG. 5 is a left side elevation view of the tote bag.

FIG. 6 is a right side elevation view of the tote bag.

FIG. 7 is a top plan view of the tote bag; and,

FIG. 8 is a bottom plan view of the tote bag.

The broken lines shown in the drawings represent portions of the tote bag that form no part of the claimed design.
